PUSH BUTTON CONTROLLED SHEET MATERIAL FEEDING APPARATUS

Harry Rosenthal, Chicago, Ill.

Application May 4, 1949, Serial No. 91,275

9 Claims. (Cl. 271—2.3)

1

This invention relates to means for feeding sheet material (such as paper) in measured amounts, and particularly to means for cutting off a desired length of the sheet material automatically in response to a manual selection.

Reference is made to the copending application of James M. Shaw and Leslie I. Faus, Serial No. 682,800, filed July 11, 1946, now Patent No. 2,629,440, issued February 24, 1953, and assigned to applicant.

Paper used for wrapping bundles of various sizes customarily is cut or torn off from a roll in various lengths according to the individual bundle sizes. Where a great many of these bundles must be wrapped in the course of a day, as would be the case in a large laundry, for example, a great deal of time may be wasted in cutting off the various lengths of paper individually by hand. It is highly desirable that the operations of drawing the paper from the roll onto a wrapping table, measuring the amount of paper drawn, and cutting off the requisite length of paper, be done automatically in response to a simple manual operation such as pressing a button. In this way, the person who does the wrapping is required merely to select the proper button and then wrap the bundle with the piece of paper which has been cut off from the roll by the machine. This saves approximately one-half of the wrapping time.

In a machine such as that described above there must be included some form of a timer to control the amount of material that is fed from the roll and cut off in each operation of the machine. This timer has a movable portion which moves concurrently with the travel of the paper or other sheet material that is being fed. When the selected amount of material has been fed, the timer stops the material feed and causes a severing operation to take place. In prior timers used for this purpose it has been necessary to perform an initial setting operation upon the movable part of the timer in accordance with the amount of material that is to be cut off. For example, one of several plungers on a timer wheel might be set to operate a switch when the wheel attains a certain position, or the timer wheel might be moved into any of several predetermined positions relative to a driving wheel thereby to vary the drive ratio in accordance with the desired selection. The present invention approaches the timing problem in a different fashion whereby this initial setting movement is eliminated.

A primary object of this invention, therefore, is to provide an improved machine of the aforesaid character having a timer which does not re-

2

quire an initial setting movement, hence does not require a setting mechanism.

A further object is to provide a simple, compact and dependable timer of novel and economical construction to control the feeding of sheet material in measured amounts.

A still further object is to facilitate preadjustment of the timer whereby the various lengths of material which can be fed by the machine are determined independently of each other.

A feature of the invention is the provision of a timer having a series of individually adjustable timing cams mounted on a common cam shaft to which a timer wheel also is secured. Associated with each cam is an individual switch electrically connected through an individual circuit to one of the push buttons controlled by the operator. When the operator presses a button, this establishes an operating circuit through a corresponding one of the cam-controlled timer switches, and sheet material is fed by the machine until the corresponding cam reaches a position where it opens the aforesaid switch. The closing of the individual circuit by the push button takes the place of the mechanical setting operation that has been required heretofore.

Another feature is the provision of a timer comprising the timer wheel and timer cams which are bodily movable as a unit, in the course of which movement the wheel is brought into and out of operative engagement with a driving roller. A solenoid performs the function of moving the timer in this fashion.

Still another feature is the provision of a simple resetting means in the form of a restoring spring on the timer wheel for returning all of the timer cams to their home positions when the wheel is disengaged from its driving roller.

The foregoing and other objects, features and advantages of the invention will be better understood from a study of the following description taken in connection with the accompanying drawings, wherein:

Fig. 1 is a perspective view of a machine embodying the invention, together with an associated gaging apparatus;

Fig. 2 is a side elevation of the machine with certain parts of the housing broken away;

Fig. 3 is a vertical section taken on the line 3—3 of Fig. 2;

Fig. 4 is an elevational view of the timer;

Fig. 5 is a diagram showing the electrical circuits of the machine; and

Fig. 6 is a diagram showing a modified arrangement of the circuits.

In the illustrated embodiment of the inven-

tion, a timer wheel is supported on a pivoted frame for movement into and out of engagement with a driving friction roller which rotates in timed relation with the roller that feeds the paper. A solenoid is provided for rocking the timer frame. Mounted on the same shaft with the timer wheel is a series of individual timer cams, and associated with each cam is an individual timer switch adapted to be operated thereby. The switches and cams move bodily with the timer wheel. As the wheel rotates, the switches are caused to operate in a predetermined sequence. For example, a plurality of switches may initially be in a closed position and then be opened in sequence as their cams rotate. The push buttons controlled by the operator are respectively related to the cam-controlled switches through the medium of individual control circuits. When a button is pressed, the paper starts to feed and the timer cams commence rotating. When the timer switch corresponding to the pressed button is operated by its cam, a control operation takes place, in the course of which the timer wheel is disengaged from its driving roller, the paper feed is suspended and a knife is actuated to shear the paper which has been fed from the roll. A restoring spring on the timer wheel returns all of the timer cams to their home positions when the timer wheel is disengaged from its driving roller.

Referring now to Fig. 1, the machine 12 is positioned near the end of a belt conveyor 13 on which bundles of laundry 14 or the like are placed prior to being wrapped. The machine 12 has a flat wrapping table 16 which is substantially on the same level as the conveyer 13. A severing mechanism is concealed within a guard or cover 18 at the rear of the table 16, and paper is fed out through a slot 20 in this guard onto the table 16. The operator controls the amount of paper which is to be fed and cut off by means of push buttons 22 located near the front edge of the wrapping table 16. In order that the operator can gage accurately the amount of paper which is required, there is provided near the conveyer 13 a standard 24 on which are mounted various indices 26 in vertically spaced relation. The indices 26 and the buttons 22 may have various colors to aid the operator in selecting the proper button. The buttons 22, for example, are colored black, red, walnut and ivory, respectively. The indices 26 are colored in a corresponding manner, and they are located at different heights on the standard 24.

The various bundles as 14 generally will have substantially uniform lengths and widths, but their thicknesses will vary. Thus, the bundle 14 may have a thickness such that the top of the bundle comes even with or just below the red index, which would be the second index 26 from the bottom. This indicates to the operator that he should press the second, or red-colored, one of the buttons 22. The machine thereupon feeds the appropriate amount of paper onto the wrapping table 16 and cuts off this length of paper. The operator lifts the bundle of laundry 14 onto the severed piece of paper and wraps the bundle in this paper. A dispensing device 28 on the table 16 furnishes strips of glued paper for sealing the bundles.

The lower part of the machine 12, below the wrapping table 16, is enclosed by a housing 30. On the right-hand side of the machine, as viewed in Fig. 1, there is a removable panel 32 behind which are disposed most of the operative mecha-

nisms of the machine. As shown best in Figs. 2 and 3, these mechanisms are supported by a vertical wall or frame plate 34. They include the timer unit 36 and two electric motors 38 and 40. The motor 40 drives a feed roller 42 which draws a web of paper 44 from a roll 46. The roll 46 rests loosely on a support provided by metal straps 48. Preferably a heavy rod 50, indicated in Fig. 2, is placed in the center of the roll 46 to weigh it down. The timer unit 36, in response to the selective actuation of the push buttons 22 (Fig. 1), regulates the amount of paper which is fed by the feed roller 42. The upper end of the web 44 advances beneath a knife 52 having a serrated cutting edge (as shown best in Fig. 3) and onto the wrapping table 16. At the appropriate time, the feeding of the paper web is arrested, and the motor 38 operates the knife 52 to sever the measured length of paper from the web 44.

A hold-down roller or series of rollers 54 presses the paper web 44 against the top of the feed roller 42. This roller 54 is rotatably mounted on a shaft 55 which is fixed at its ends to a pair of pivotally mounted arms 56. Cane-shaped rods 58 are rotatably supported in upright positions and are subject to spring tension which tends to urge these rods downwardly. The offset upper ends of the rods 58 are adapted to be received in suitable notches provided in the pivoted arms 56. When a new roll of paper is being inserted in the machine, the rods 58 are lifted and turned to disengage their upper ends from the arms 56 and thereby release the arms 56. The hold-down roller 54 then is raised so that the end of a paper web as 44 may be inserted between the rollers 42 and 54. The parts then are restored to their original positions, with the roller 54 being sprung-urged into engagement with the feed roller 42.

The knife 52 is operated by a bell crank 60, Fig. 2, carrying a follower which cooperates with a cam 62 driven by the motor 38. Each time the cam 62 rotates, it rocks the bell crank 60 and causes the knife 52 to descend for severing a length of paper from the web 44. The knife 52 is restored to its upper position by suitable springs as 64 acting upon an arm of the bell crank 60.

Referring now to Figs. 2, 3 and 4, the timer unit 36 is mounted on the wall 34 and is covered by a guard or housing 70. The timer proper is carried by a pivoted frame 72, which supports a cam shaft 84, a timer wheel 74, a series of timer cams 76 and 78, and a corresponding series of timer switches 80 and 82. The timer wheel 74 and the cams 76 and 78 are mounted on and secured to the cam shaft 84, which is journaled in the frame 72. The frame 72 is pivoted as indicated at 86, Fig. 4, and is connected by a spring 88 to the core of a solenoid 90, the coil of which is fixed in position.

When the solenoid 90 is energized, it causes the timer frame 72 to be rocked on its pivot 86 for bringing the timer wheel 74 into engagement with a knurled driving roller 92, Figs. 2 and 3. The timer wheel 74 has a rubber tread on its periphery to afford a good frictional coupling with the roller 92. The roller 92 rotates with a pulley 94 that is connected by a belt 96 to a pulley 98 on the shaft of the feed roller 42. The driving roller 92 therefore is rotated in timed relation with the feed roller 42, that is to say, in timed relation with the feeding of the paper web 44.

When the solenoid 90 is deenergized, the wheel 74 is withdrawn from the roller 92 by gravity. A spiral spring 100, Fig. 4, restores the timer

wheel 74 and cam shaft 84 to their initial positions when this disengagement is effective. A small angle piece or stop 102 secured to the wheel 74 strikes against a bumper 104 mounted on the frame 72 to arrest the timer wheel 74 and cam shaft 84 in their home positions.

Associated with the timer proper are certain stationarily mounted relays 108, 112 and 122, which are shown in elevation in Fig. 4 and are schematically illustrated in Fig. 5. Relay 108 has normally open contacts 140. Relay 112 has normally open contacts 114 and 116 and normally closed contacts 118 and 120. Relay 122 has normally open contacts 124 and 126. Electrical connections (not shown in Fig. 4 but represented in Fig. 5) are made from the various electrical parts of the timer unit 36 to a series of terminals numbered 1 to 11 disposed on a terminal strip 128.

The operation of the illustrated machine will be described with reference to Fig. 5. The machine is readied for operation by closing an on-off switch 130. The operator then presses one of the buttons 22 according to the amount of paper which he desires. Each of the buttons 22 controls a switch 132, and as a button is pressed, it closes its switch 132. In the present embodiment of the invention these switches 132 are assumed to be of the type which, once they are closed, remain closed until they are mechanically reset. The switches 132 selectively establish circuits from one of the main conductors 134 to the terminals 1 to 4, respectively. These circuits continue from the terminals 1 to 4 respectively through the cam-controlled timer switches 80 to the winding of the relay 112. From this relay winding the circuit is completed through terminal 6 to the other main conductor 136. It will be noted that the timer switches 80 normally are closed when their timer cams 76 are in home position. Closure of a push button switch 132 (for example, the one operated by the second push button 22) therefore closes a circuit through the corresponding terminal (No. 2 in this instance) and the corresponding timer switch 80 for energizing the relay 112. Relay 112 remains energized until this circuit is broken.

Relay 112, when energized, closes its contacts 114 and 116 and opens its contacts 118 and 120. The opening of contacts 118 and 120 is without effect at the present time. Closure of contact 116 establishes a circuit from the main conductor 134 through terminal 5, conductor 142, winding of the timer solenoid 90, contact 116 and terminal 6 to the main conductor 136. The solenoid 90 thereupon is energized and it rocks the timer frame to bring the timer wheel 74 into engagement with its driving roller 92. The effect of this will be described presently.

Closure of relay contact 114 completes a circuit from the main conductor 134 through terminal 5, contact 114, winding of relay 122, terminal 10, conductor 138 and a limit switch 140 to the other main conductor 136. The limit switch 140 normally is closed and is opened only momentarily toward the end of a severing operation. Switch 140 being closed in the present instance, the relay 122 therefore energizes to close its contacts 124 and 126. The closure of relay contact 124 is without effect at the present time. The closure of relay contact 126 establishes a holding circuit for the relay 122, which holding circuit extends from terminal 5 through conductors 142 and 144, contact 126, conductor 146, winding of relay 122, terminal 10, conductor 138 and limit switch 140.

Closure of the relay contact 116, in addition to energizing the timer solenoid 90, also establishes a circuit through terminal 7 and conductor 137 to the main motor 40, which effects the paper feed. A brake solenoid 139 is connected in parallel with the motor 40, so that the motor 40 and solenoid 139 are energized concurrently. The solenoid 139 is arranged to release a brake from the motor shaft when it is energized and apply this brake to the motor shaft when the solenoid is deenergized. The motor 40, when energized, drives the feed roller 42 to advance the paper web 44 beneath the knife 52, Fig. 2.

As the motor 40 and solenoid 90 are energized in the manner described above, the driving roller 92 commences rotating and the timer wheel 74 is brought into engagement therewith. The cams 76 and 78 thereupon commence rotating away from their home positions. After a few degrees of movement, the cam 78 actuates its switch 82, causing this switch to open its back contact and close its front contact. Such action is without effect at the present time. As previously explained, the timer switches 80 normally are closed. As the cams 76 rotate, the low portions of these cams move toward their respective switches 80. For the maximum length of paper, a complete sequence of switch operations will take place, and the four cams 76 will cause the switches 80 to open at different times. This sequence of operations is only partially executed when a sheet less than the maximum length is to be severed from the paper web.

It has been assumed, for example, that the second push button 22 was depressed. The operating circuit for the relay 112 therefore remains established only so long as the second cam switch 80 remains closed. When the flat spot on the second cam 76 is presented to the cam follower on the switch 80, the switch opens and breaks the circuit through the winding of relay 112. Relay 112 thus is deenergized. Contact 116 of this relay opens and interrupts the circuit through the timer solenoid 90 and the main motor 40, causing them to be deenergized. The brake solenoid 139 also is deenergized for quickly applying the brake to the motor 40. As the timer wheel 74 becomes separated from the driving roller 92, the restoring spring 100 starts to move the wheel 74 and the cams 76 and 78 back toward their home positions.

When relay 112 deenergizes, it opens its contact 114, but this is without effect at present inasmuch as the relay 122 is being held energized through the aforesaid holding circuit. The relay contact 120 closes and establishes a circuit from the conductor 136 through the limit switch 140, conductor 138, terminal 10, the front contact of the timer switch 82 (now closed inasmuch as the cam 78 is not fully restored as yet), relay contact 120, terminal 9, and conductor 148 to the reset solenoid 150 and counter 152, from whence the circuit is completed to the conductor 134. The brief pulse of current through this circuit which occurs while the front contact of the timer switch 82 is still closed causes the counter 152 to be advanced one digit and also operates the solenoid 150 to reset the closed one of the push button switches 132. All of the switches 132 now are in their open positions.

As the timer cam 78 reaches its home position, the back contact of the switch 82 closes. This establishes a circuit from terminal 5 through the conductors 142 and 144, contact 124 of relay 122, conductor 154, winding of relay 108, contact 118

of relay 112 (now closed), back contact of switch 82, terminal 10, and limit switch 140. Relay 108 energizes and closes its contact 110. This closes a circuit from terminal 5 through contact 110, terminal 8 and conductor 156 to the knife motor 38. Motor 38 energizes and drives the knife for cutting off the portion of the paper web which has advanced past the knife. The cam 160 is driven by the motor 38, and as this cam nears the end of its revolution, it opens the limit switch 140 momentarily. Opening of the switch 140 breaks the holding circuit for the relay 122, causing this relay to deenergize and open its contacts 124 and 126. The relay 108 thereupon is deenergized to open its contact 110. As a result the knife motor 38 is deenergized and stops rotating. The momentum of the motor 38 is just sufficient to carry the rise on the cam 160 past the limit switch 140, permitting this switch to close again in readiness for the next operation of the machine. All parts of the system now have been restored to their initial condition.

There may be instances in which it is desired to operate the knife independently of the push buttons 22. For example, the machine may inadvertently come to rest with the limit switch 140 held in an open position. Under these circumstances the actuation of a push button 22 would not result in a paper severing operation. In view of this, there has been provided another push-button switch 162, Figs. 1 and 5, of the momentary contact type. This switch has two sets of contacts 164 and 166, both of which are closed when the button 162 is pressed. The contact 166, when closed, bridges the limit switch 140. Contact 164, when closed, establishes a circuit from the main conductor 134 to terminal 11, from which a conductor 170 leads to the conductor 146, the circuit then being completed through the winding of relay 122, terminal 10 and contact 166 to the main conductor 136. As relay 122 energizes, it closes its contact 124 which, in the manner hereinabove described, completes a circuit through the back contact of the timer switch 82, relay contact 118 and winding of relay 108. Relay 108 energizes and causes the knife motor 38 to go through a cycle of operation. The push button 162 should be released the instant that the knife starts to descend, leaving the limit switch 140 in control. Relays 108 and 122 remain energized until the switch 140 opens and breaks the holding circuit for relay 122.

The illustrated machine has numerous advantages which are apparent from the foregoing description. The timer assembly is compact, rugged and accurate in its operation. The various timer cams 76 can be individually adjusted independently of each other to determine the various lengths of paper which will be fed when the push buttons 22 are actuated. For convenience, these cams 76 may be individually colored to correspond with the colors of the push buttons with which they are associated. They effect a positive control over the operation of the machine through the medium of the timer switches 80. The mechanical operation is simplified because of the fact that the timer is not required to perform an initial setting movement in addition to its rotative movement. The mere closure of an electric circuit by pressing a push button 22 is all that is necessary to start the timer operating and control the amount of paper which is fed. Since each of the cams 76 can be separately adjusted without affecting the other cams, the machine can be adapted for a variety

of uses in which paper sheets of many different lengths must be furnished automatically in response to manual selections.

Fig. 6 illustrates a modified circuit arrangement which differs from Fig. 5 in that push button switches 170 of the momentary-contact type are used in place of the mechanically interlocked push button switches 132. Corresponding parts of the circuits shown in Figs. 5 and 6 bear like reference characters and perform substantially the same functions in both cases. In Fig. 6, hold-down relays 172 are respectively associated with the push buttons 170. Each relay has a pair of normally open contacts 174 and 176, the functions of these relay contacts being explained more fully hereinafter. The contact 174 of each relay 172 is part of an electrical holding circuit which is controlled by one of the timer switches 80. Whenever a push button 170 is actuated, the corresponding relay 172 is energized (under normal conditions of operation), and this relay locks itself up through its holding circuit, permitting the push button 170 to be released while the relay is held energized. The locked-up relay 172 is not released until the associated timer switch 80 is opened by its cam 76.

All of the relays shown in Fig. 6 are low-voltage alternating-current relays. A transformer 178 is employed to step down the commercial line voltage to the required low value for operating these relays. Conductors 180 and 182 extend respectively from the alternating current line wires (not shown) to the terminals 5 and 6. The primary winding 184 of the transformer 178 is connected across these terminals. The secondary winding 186 of the transformer 178 furnishes the low voltage for energizing the relays.

The operation of the machine schematically illustrated in Fig. 6 will now be described. The operator selects and actuates one of the push buttons 170 according to the amount of paper which is desired. This closes a circuit from the transformer secondary 186 through a normally closed contact 188 of a relay 190 and through the actuated push button 170 to the corresponding relay 172. This relay 172, upon energizing, closes its contacts 174 and 176. Closure of the contact 176 establishes a holding circuit for the relay 172, which holding circuit extends through the associated cam-controlled timer switch 80. This action takes place practically instantaneously, so that the push button 170 need be depressed only momentarily and then is immediately released. The push button switch opens when released, but the corresponding relay 172 remains energized through the aforementioned holding circuit for that relay. In this embodiment of the invention no special reset mechanism is required for the push buttons 170.

When the contact 174 included in any of the relays 172 closes, a circuit is established from the transformer secondary 186 through the winding of a relay 192. Relay 192 energizes, causing its contacts 194 and 196 to open and its contact 198 to close. The closure of relay contact 198 establishes a circuit which extends from the transformer secondary 186 through the winding of a relay 200, thence through terminal 10, limit switch 140 (closed at this time) and terminal 13 back to the secondary 186. Relay 200 energizes and causes its normally open contacts 202 and 204 to close. The closure of relay contact 202 establishes a holding circuit for the relay 200. The closure of relay contact 204 is without effect at the present time. Thus, it will be seen

that relays 192 and 200 are energized as an incident to the energization of any one of the relays 172.

When any one of the relay contacts 174 closes as described above, it also establishes a circuit from the transformer secondary 186 through the winding of another relay 206 having a normally open contact 208. This contact 208 closes in response to the energization of relay 206 and thereby closes a circuit from the line-voltage conductors 180 and 182 through the timer solenoid 90 and the main motor 40 of the machine.

As the motor 40 rotates, it drives the paper feed in the manner described previously, and it also causes the driving roller 92, Fig. 6, to rotate.

The timer solenoid 90, when energized, brings the timer wheel 74 into engagement with the driving roller 92, and the timer cams 76 and 78 thereupon commence rotating. The cams 76 cause their switches 80 to open in sequence as the timer wheel 74 rotates. When the timer switch 80 corresponding to the energized relay 172 opens, the holding circuit for that relay is broken and the relay deenergizes, causing its contacts 174 and 176 to open. In consequence of this, the relays 192 and 206 are deenergized. The deenergization of relay 206 brings about the deenergization of the solenoid 90 and the motor 40, thereby interrupting the paper feed and causing the timer wheel 74 to be disengaged from the driving roller 92. A brake mechanism 139 may be associated with the motor 40, if desired.

As relay 192 is released, its contacts 194 and 196 close. At the instant when this occurs, the timer cam 78 is still maintaining its front contacts closed. This causes a circuit to be completed from the transformer secondary 186 through the relay contact 194 and terminals 9 and 12 to the counter 152. The counter 152 thereby is advanced one digit. When the timer cam assembly is restored to its initial position by the restoring spring 100 on the timer wheel 74, the front contacts of the timer switch 82 are opened, interrupting the circuit through the counter 152.

When the timer cam assembly is fully restored, the back contacts of the timer switch 82 close, causing a circuit to be completed from the transformer secondary 186 through the relay contacts 196 and 204 to the winding of the relay 190. Relay 190 thereupon energizes, causing its contact 188 to open and its contact 189 to close. The opening of relay contact 188 prevents any of the relays 172 from becoming energized while the relay 190 is energized. The closure of relay contact 189 initiates a paper severing operation by extending a circuit from the line conductors 180 and 182 through the knife motor 38. As the motor 38 rotates, it drives the knife mechanism for severing a sheet of paper from the roll in the manner described previously. The length of the paper sheet cut off by the knife is, of course, determined by the selective actuation of a push button 170. As the knife completes its severing operation, it is restored to its upper position. Near the end of this cycle, the cam 160 momentarily opens the limit switch 140, thereby interrupting the holding circuit for the relay 200. Relay 200 thereupon deenergizes, and in so doing, it causes the relay 190 to become deenergized. Thus, all of the relays have now been released, and the machine is in readiness for another cycle of operations.

The momentary-contact switch 162 serves the same purpose in Fig. 6 as it did in Fig. 5. That is, it may be employed to send the knife mecha-

nism through a cycle of operation independently of the push buttons 170. This switch 162 is used in case the machine comes to rest with the limit switch 140 held in its open position. As the push button 162 is pressed, the associated contacts 166 bridge the limit switch 140, and the contacts 164 close a circuit to the relay 200. This results in the energization of relays 200 and 190, bringing about a new cycle of the knife mechanism.

While the invention has been disclosed with reference to several preferred embodiments thereof, it should be understood that the principles of the invention apply equally well to other modifications coming within the spirit of the appended claims.

I claim:

1. Apparatus for feeding measured amounts of sheet material including in combination, controllable sheet material feeding means, a plurality of control members each of which is operable to initiate operation of said feeding means and select a predetermined amount of sheet material to be fed by said feeding means, a corresponding plurality of control devices each of which includes portions movable with respect to each other in timed relation with the movement of the sheet material, one of said portions of each device being adjustable for determining the respective times at which each of said control devices is operated during the travel of the sheet material, and means controlled by said control members and by said control devices for interrupting the feed of sheet material by said feeding means in response to the operation of a control device corresponding to an operated control member.

2. Apparatus for feeding measured amounts of sheet material including in combination, controllable sheet material feeding means, a plurality of individually operable control members for initiating operation of said feeding means and for selecting the amount of sheet material to be fed by said feeding means, a corresponding plurality of control devices each including portions movable with respect to each other in timed relation with the movement of the sheet material, one of said portions of each device having an adjustable initial position for determining the respective times at which said control devices are operated during the travel of the sheet of material, means controlled by said control members and by said control devices for interrupting the feed of sheet material by said feeding means in response to the operation of a control device corresponding to an operated control member, and means for automatically restoring said portions of said control devices to predetermined initial positions after each operation of said feeding means.

3. Apparatus for feeding measured amounts of sheet material including in combination, controllable sheet material feeding means, and a control system for controlling said feeding means including a plurality of circuits, each of said circuits including first and second switches, said first switches having push button operating members for controlling the same, and adjustable means for actuating said second switches, said adjustable means and said second switches being movable with respect to each other in timed relation with the movement of said sheet material so that said second switches are actuated in a particular sequence as said sheet material is fed, said control system causing operation of said feeding means in response to operation of

any one of said first switches and causing said feeding means to stop when said second switch in the circuit with said one first switch is actuated.

4. Apparatus for feeding measured amounts of sheet material including in combination, controllable sheet material feeding means, a plurality of control means each being individually operable for initiating operation of said feeding means and for selecting an amount of sheet material to be fed by said feeding means, a corresponding plurality of control devices individually associated with said control means, a plurality of timing members movable in timed relation with the movement of the sheet material and cooperating individually with said control devices for operating the same in sequence, said timing members being individually adjustable to any position within a predetermined range for determining the respective times at which said control devices are operated during the travel of the sheet material, and stop means connected to said control means and to said control devices for interrupting the feed of sheet material by said feeding means in response to the operation of a control device corresponding to an operated control means.

5. Means for timing the operation of sheet material feeding apparatus including, a rotatable driving member for the feeding apparatus, a movably mounted frame, a shaft journaled in said frame, a driven member on said shaft frictionally engageable with and disengageable from said driving member, a plurality of cams mounted on said shaft, a plurality of switches respectively associated with said cams, said cams having portions thereon for actuating said switches and being individually adjustable on said shaft for actuating said switches respectively at predetermined times during the rotation of said shaft, actuating means for moving said frame to a position to provide frictional engagement between said driving and driven members so that said cams move with respect to said switches in accordance with the amount of sheet material that has been fed during said engagement, and selectively operable electrical means coupled to said switches and operating in response to the actuation of a selected switch by its associated cam to disable said actuating means, to thereby produce disengagement of said members when a selected amount of sheet material has been fed.

6. A machine for feeding various selected lengths of sheet material from a roll including in combination, sheet material feeding means, driving means for said feeding means, a series of individually operable contact devices, a timer mechanism including a series of cams and a series of switches respectively cooperating with said cams, electrically operable means controlled in part by said contact devices for initiating operation of said driving means and for establishing an operative connection between said feeding means and said timer mechanism when one of said contact devices is actuated, and a plurality of control circuits respectively extending through said contact devices and said switches to said electrically operable means and effective when the switch corresponding to the operated one of said contact devices is operated by its respective cam to disable said feeding means and to interrupt the operative connection between said timer mechanism and said feeding means.

7. A machine for feeding various selected

lengths of sheet material from a roll including in combination, sheet material feeding means, driving means for said feeding means, a series of individually operable contact devices, a timer mechanism including a cam shaft and a series of cams individually mounted on said shaft, said timer mechanism also including a series of switches respectively cooperating with said cams, electrically operable means controlled in part by said contact devices for controlling the operation of said feeding means by said driving means and for establishing an operative connection between said feeding means and said cam shaft when any one of said contact devices is actuated, and a plurality of control circuits respectively extending through said contact devices and said switches to said electrically operable means and effective when the switch corresponding to the operated one of said contact devices is operated by its respective cam to disable said feeding means and to interrupt the operative connection between said timer mechanism and said feeding means, said timer mechanism operating to automatically restore said cams to a given initial position thereof after each feeding operation.

8. Apparatus for feeding sheet material on a wrapping table for wrapping articles therein including in combination, gauge means including a plurality of readily distinguishable indices thereon adapted to be positioned adjacent to articles to be wrapped to indicate the size thereof, means for holding a roll of sheet material, controllable feeding means for feeding sheet material from said roll, a plurality of control members individually corresponding in appearance to said indices and individually operable for initiating operation of said feeding means and for selecting predetermined lengths of sheet material required for wrapping the articles gauged, a corresponding plurality of control devices including portions coupled to said feeding means and operating automatically in sequence as said predetermined lengths of sheet material are fed, and means controlled by said control members and said control devices for interrupting the feed of sheet material by said feeding means in response to the operation of a control device corresponding to an operated control member, said portions being adjusted to such positions that the length of sheet material fed in response to the operation of any control member is the length of sheet material required to wrap articles of a size which correspond to the index on said gauge means associated with said control member operated.

9. Apparatus for feeding measured amounts of sheet material on a wrapping surface for wrapping articles therein including in combination, a frame structure having a substantially horizontal wrapping surface, means supported on said frame structure for holding a roll of sheet material, controllable sheet material feeding means for feeding the sheet material from said roll onto said wrapping surface, a plurality of push button control means at said top surface each being individually operable for initiating operation of said feeding means and for selecting an amount of sheet material to be fed by said feeding means, a corresponding plurality of control devices individually associated with said control means, a plurality of timing members movable in timed relation with the movement of the sheet material and cooperating individually with said control devices for operating the same.

in sequence, said timing members being individually adjustable to any position within a predetermined range for determining the respective times at which said control devices are operated during the travel of the sheet material, and stop means connected to said control means and to said control devices for interrupting the feed of sheet material by said feeding means in response to the operation of a control device corresponding to an operated control means.

HARRY ROSENTHAL.
